UNITED STATES PATENT OFFICE.

JAMES CASEY, OF MINNEAPOLIS, MINNESOTA, ASSIGNOR OF ONE-HALF TO
JAS. F. WILLIAMSON, OF SAME PLACE.

AUTOMATIC CHOKE-FEED DEVICE FOR LUBRICATORS.

SPECIFICATION forming part of Letters Patent No. 624,624, dated May 9, 1899.

Application filed March 26, 1897. Serial No. 629,332. (No model.)

To all whom it may concern:

Be it known that I, JAMES CASEY, a citizen of the United States, residing at Minneapolis, in the county of Hennepin and State of Minnesota, have invented certain new and useful Improvements in Automatically-Adjustable Choke-Feed Devices for Cylinder-Lubricators; and I do hereby declare the following to be a full, clear, and exact description of the invention, such as will enable others skilled in the art to which it appertains to make and use the same.

My invention has for its object to provide an improved choke-feed for cylinder-lubricators.

The choke-feed now in general use on cylinder-lubricators will affect the feed of the oil to the valve-chest and cylinders in sufficient quantities as long as there is sufficient difference of pressures in the lubricator and in the cylinder-pipe. Otherwise stated, as long as the throttle-valve is partly closed the ordinary choke-feed will supply the needed oil; but if the throttle be wide open, as when the engine is dragging a heavy load on a steep grade, or for any reason, the pressure in the valve-chest and cylinder-pipe will approximate so closely to that in the lubricator that sufficient oil will not be fed through the ordinary choke-plug. Still, otherwise stated, if the contracted passage in the choke-plug be adapted for the desired supply of oil, when working the engine with the steam more or less throttled, the lubricator will not supply sufficient oil when the throttle is wide open.

My invention has for its object to overcome this defect, which I accomplish by providing a choke-feed of extremely simple construction, which will automatically adjust itself so as to afford a free and sufficient supply of oil under all conditions.

To these ends my invention consists of the novel features hereinafter described, and defined in the claims.

The invention is illustrated in the accompanying drawings, wherein like letters refer to like parts throughout the several views.

Figure 1 is a view, chiefly in longitudinal central section, through my improved choke-feed and the pipe connections containing the same, with the feed devices in the position

which they will occupy when using steam more or less throttled. Fig. 2 is a similar view of the same parts with the feed devices shown in the position which they would assume when the throttle-valve is wide open. Fig. 3 is a view in perspective showing the feed devices detached and pulled apart from each other.

The reference-letter *a* represents a part of the lubricator.

a' represents a fitting connecting with the lubricator and containing the choke-feed devices.

a² represents a fitting connecting the fitting *a'* and the cylinder-pipe *a³*. The parts *a²* and *a³* are united by a suitable coupling *a⁴*, which affords a tight joint. The fitting *a²* is equipped with an ordinary oil-cup *a⁵*.

Having regard now to the choke-feed devices, the fitting *a'* is suitably bored out to afford a seat for a choke-block *b* and a differential piston *c*. The choke-block *b* is fixed in the fitting *a'* at the cylinder end of the same, and the differential piston *c* is free for limited movement in the bore of the same on the lubricator side of the choke-block *b*. The choke-block *b* is provided with a choke-plug *b'*, having the ordinary contracted or choke passage *b²*. The choke-block *b* is also provided with one or more by-passages *b³*. As shown, there are several of these by-passages *b³*, and the choke-block is counterbored, as shown at *b⁴*. The choke-plug *b'* is shown as projecting toward the differential piston beyond the end of the body of the block and as provided with a conical end.

The differential piston *c* is provided with a central passage *c'*, of considerably larger size than the choke-passage *b²* in the choke-plug *b'*. The passage *c'* in the piston terminates in a bell-mouth *c²*, which is adapted to fit over the conical end of the choke-plug *b'* when the parts are in the position shown in Fig. 1. The smaller member *c³* of the differential piston faces the lubricator and is subject to lubricator-pressure. The larger member *c⁴* of the differential piston faces the choke-block *b* and is subject to cylinder-pressure through the passages *b³* in the choke-block *b*. In virtue of this construction and disposition of the said choke-feed devices the action will be as fol-

lows: Within the predetermined limit of variation between the pressure in the lubricator and the pressure in the cylinder-pipe, or, otherwise stated, when the steam is being throttled, the parts will be held in the position shown in Fig. 1 by the sufficiently greater pressure from the lubricator on the smaller piston member c^3 , and when the said parts are in said position (shown in Fig. 1) it is obvious that the larger passage c' in the piston c can only coöperate with the contracted or choke passages b^2 in the choke-plug b' . Whenever the pressure in the cylinder-pipe increases beyond the predetermined limit of variation, so as to approximate the pressure in the lubricator, the parts will be moved into the position shown in Fig. 2 in virtue of the larger size of the differential piston member c^4 , and when this occurs it is obvious that the larger passage c' in the differential piston will coöperate with all the passages in the choke-block b . In virtue of the increased aggregate area of the passages thus rendered available through the choke-block b it is obvious that a much larger quantity of steam will be permitted to flow through from the lubricator into the cylinder-pipe. Hence, although the pressure in the cylinder approximates that in the lubricator, sufficient oil will be carried through for lubricating the engine-valves and the cylinder under the reductions which take place from the movements of the engine-piston.

From the foregoing description it must be obvious that if the parts be properly proportioned my choke-feed may be made so as to deliver a substantially uniform amount of oil to the valve-chest and cylinder under all conditions of the steam-pressure. Otherwise stated, when the steam is being throttled the parts will occupy the position shown in Fig. 1 and my improved choke-feed will operate like the ordinary choke-feed, supplying the oil through the contracted passage of the choke-plug b' only; but when the throttle is wide open, so that the pressure in the valve-chest and cylinder-pipe approximates much more nearly to that in the lubricator, the parts will assume the position shown in Fig. 2, so as to render the larger area of openings available through the choke-block b , and thereby permitting the desired feed of the oil from the lubricator. My choke-feed is therefore auto-

matically adjustable for securing a substantially uniform feed.

By actual observation as a locomotive-engineer I have observed the defects of the ordinary choke-feed, as stated at the beginning of this specification, and by actual usage I have demonstrated that my improved choke-feed herein disclosed overcomes the said defect and affords the free and substantially uniform feed of the oil under all conditions.

What I claim, and desire to secure by Letters Patent, is as follows:

1. An automatically-adjustable choke-feed for cylinder-lubricators, comprising a fixed choke-block having a choke-plug and one or more by-passages, and a differential piston, on the lubricator side of said block, with its smaller member subject to lubricator and its larger member subject to cylinder-pressure, the said differential piston having a passage of larger size than the choke-passage in said plug, with said parts so arranged that, under the normal difference of pressures said piston seats on said plug and its passage coöperates with the choke-passage in said plug only, but that whenever said difference of pressures becomes less than normal, said piston moves away from said plug and its passage coöperates with all of the passages in the choke-block, substantially as and for the purposes set forth.

2. The choke-feed, for cylinder-lubricators, comprising a suitable casing a' , the fixed choke-block b having the choke-plug b' with choke-passage b^2 and provided also with the by-passages b^3 , the differential piston c on the lubricator side of said block having the passage c' of larger size than the choke-passage b^2 , with its smaller piston member c^3 subject to lubricator-pressure and its larger member c^4 subject to cylinder-pressure, and said piston being arranged to seat on said plug, under the normal difference of pressures and to move away from said plug when the difference of pressure becomes less than normal, substantially as and for the purposes set forth.

In testimony whereof I affix my signature in presence of two witnesses.

JAMES CASEY.
